UNITED STATES PATENT OFFICE.

ERNEST PHILLIPS, OF NEW HAVEN, CONNECTICUT, ASSIGNOR TO THE YALE TIRE & RUBBER CO., OF NEW HAVEN, CONNECTICUT, A CORPORATION.

DESIGN FOR A TIRE.

59,511.

Specification for Design.

Patented Oct. 25, 1921.

Application filed July 23, 1920. Serial No. 398,591. Term of patent 14 years.

To all whom it may concern:

Be it known that I, ERNEST S. PHILLIPS, a citizen of the United States, residing at New Haven, in the county of New Haven and State of Connecticut, have invented a new, original, and ornamental Design for a Tire, of which the following is a specification, reference being had to the accompanying drawing, forming part thereof.

Figure 1 is a face view of a portion of a tire showing my new design.

Fig. 2 is a sectional view on the line 2—2 of Fig. 1.

I claim:

The ornamental design for a tire, as shown.

ERNEST S. PHILLIPS.
